UNITED STATES PATENT OFFICE.

FRANCIS X. GANTER, OF BALTIMORE, MARYLAND.

PARQUET FLOORING OR PANELING AND METHOD OF MAKING THE SAME.

1,102,036.

Specification of Letters Patent. Patented June 30, 1914.

Application filed April 5, 1910. Serial No. 553,512.

To all whom it may concern:

Be it known that I, FRANCIS X. GANTER, a citizen of the United States, residing at Baltimore, in the State of Maryland, have 5 invented new and useful Improvements in Parquet Flooring or Paneling and Methods of Making the Same, of which the following is a specification.

In laying parquet flooring it is necessary, 10 under present methods and with the means now in common use, to first construct an under flooring or base, then lay the parquetry blocks thereon, and finally plane and polish the surface of the floor so produced. 15 This requires several separate and distinct operations as well as careful and skilled workmanship in order to secure good results, and consequently the construction of such floors is costly. The appearance of the 20 floor is also marred by the use of tacks or nails to secure the blocks to the base, through warping of the floor from lack of uniformity in the seasoning and unequal expansion and contraction of its component 25 parts, and frequently through the inability of the workman to assemble the blocks in such manner as to present an artistic design.

One of the objects of the present invention is to provide a novel construction of 30 parquetry boards embodying in a single article both the base and the finished parquetry surface and which may be laid to form the floor in a single operation, thus reducing the cost of laying any floor of a 35 given size to a considerable extent.

Another object of the invention is to provide parquetry boards of this character which may be laid to produce any given design according to an established pattern, 40 which will obviate the use of nails or other fastenings liable to mar the appearance of the floor, which when laid will require little or no planing or like surface finishing and will not be liable to shrink or warp, and 45 which may also be used for wall and ceiling paneling.

Still another object is to provide a method of rapidly and economically producing parquetry boards embodying the aforesaid advantages.

In the accompanying drawings, illustrating the invention:—Figure 1 is a perspective view of a parquetry board as constructed for use. Fig. 2 is a longitudinal section 55 of the same. Figs. 3 and 4 are transverse sections on the lines 3—3 and 4—4 of Fig.

1. Fig. 5 is a cross section in perspective, showing a modification. Fig. 6 is a fragmentary perspective view illustrating the first step in the method of manufacturing 60 the boards. Fig. 7 is a similar view showing the second step in the method of manufacturing the boards. Fig. 8 is a view showing the third step of division of the stock into sections. Figs. 9, 10 and 11 are views 65 showing the successive steps of treating each stock division or section.

In carrying my invention into practice, I provide a parquetry board A comprising a base 1 and a surface 2, said board being 70 preferably of the length of an ordinary flooring board. The board is provided at one side with tongues 3 and at its opposite side with grooves 4 formed in the base and surface for interlocking connection with the 75 edges of adjacent boards in laying the floor.

The base 1 consists of a single piece of wood of any kind suitable for the purpose, while the surface 2 is formed of parquetry blocks or strips arranged in abutting contact and in any suitable manner to produce a desired floor design or surface finish. These blocks are firmly united by glue or cement 80 or other concealed fastening means to the upper surface of the base 1, and may be 85 similarly united at their meeting edges to each other to render the board strong and rigid at all portions throughout its length and breadth.

In practice, the base and surface may be 90 co-extensive in thickness, but as a general rule the base is made somewhat thicker than the surface, their relative dimensions in this particular being, however, such that the tongues and grooves may be similarly 95 formed upon and in each element, thus adapting both the base and the parquetry face of each board to interlock with the edges of contiguous boards of a floor to reinforce and secure a double interlocking engagement between the edges of the boards, thus obviating liability of any of the blocks being loosened or casually torn from their bases.

For the purpose of still further strengthening the connection between the base and parquetry surface, the meeting faces of these elements are provided on opposite sides of the longitudinal center of the board with tongue and groove connections 6. These 110 tongue and groove connections extend the full length of the elements and correspond

in number to the greatest number of transverse block sections or divisions at any point, thus firmly locking all of the blocks to the base. The tongue and groove connections 5 may be of the plain type shown in Figs. 1, 2, 3 and 4, or dovetailed as shown at 6' in Fig. 5.

In the construction of a parquet floor in accordance with my invention, the boards A. 10 are laid in the usual manner of laying an ordinary floor without a base or false flooring beneath it, the said boards being simply tongued-and-grooved together, whereby a floor having a parquet surface will be produced. Where a very solid flooring is required, the thickness of the board may be increased and if desired the boards may be secured to the floor beams 7 by nails or other fastenings 8 driven diagonally from the 15 tongued side of the board down through the surface and base and into the beams, as shown in Fig. 5. As the surface 2 of each board is planed and polished by machinery in the operation of finishing the board, practically little planing or finishing of the floor 20 surface will be required, except in instances where extreme nicety of finish is called for. By dispensing with the ordinary base and process of individually securing the parquet 25 blocks thereto, the operation of laying a floor is simplified, the cost of construction considerably reduced, and marring of the parquetry surface by the use of fastenings passing downward through the face 30 thereof obviated, while at the same time a much stronger and more durable floor is produced.

A distinct advantage arising from the construction of parquetry boards of the type 40 described is that selected wood seasoned to the same extent may be used, and by gluing the blocks to the base and allowing the glue to properly set a practically homogeneous connection is obtained which insures the production 45 of a flooring of greater solidity and strength than floors constructed in the usual manner with the parquetry blocks nailed to the foundation base. Furthermore, the parquetry finish of the boards may follow the 50 designs of skilled artists, allowing a floor of any ornamental appearance to be laid from a pattern without dependence upon the artistic skill of the workman in forming the design in the usual way. The boards are 55 also less liable to shrink or warp and mar the symmetry of surface and appearance of the floor. Owing to the strength of the bond between the base 1 and surface 2, the former 60 may be made without disadvantage of wood having knots or other imperfections rendering it unsuitable for use in an ordinary floor surface or ordinary parquetry base, with resulting economy.

In the method of manufacturing a parquetry board constructed as hereinbefore de-

scribed, a number of parquetry blocks, disposed to form a desired pattern, are assembled or built up upon one another and glued or otherwise suitably fastened together, as shown in Fig. 5, to produce an oblong rectangular board or block 9 of a length corresponding to that of the parquetry board to be made and of a thickness to enable two or more of the parquetry surfaces 2 to be formed therefrom.

As shown in Fig. 7, base boards 10 are then glued or otherwise suitably fastened to two of the opposite faces of said block 9, and the whole allowed to dry, if glued, until the glue has thoroughly set and hardened. The multiple parquet unit thus made is then divided longitudinally along the dotted line 11 to produce two corresponding sections 12 and 13, as shown in Fig. 8, each formed of a base board and a portion of the parquetry block. Said sections 12 and 13 will then constitute two parquet boards ready for finishing, if the parquet block employed is of a thickness for division into two parquet faces only. If, however, for example, the block is of suitable thickness, as shown, for making four complete boards, then other base boards 14 are glued or otherwise fastened to the exposed inner faces of the respective block sections, as shown in Figs. 9 and 10, forming other multiple boards of less thickness than the original board. Each of these multiple boards is then respectively sawed or otherwise longitudinally divided along the central line 15, thus producing four complete parquetry boards of the proper thickness for use, Fig. 11 showing a completed board ready for the finishing operation of tonguing, grooving and planing. Thus it will be seen that through this method of manufacture, two or more complete parquetry boards may be manufactured from a single multiple board, dependent upon the thickness of the original block 9, all of which boards will have a uniform surface pattern. Strength and durability of construction and economy of production are thus secured. It will be understood, however, that, while this method of manufacture is preferred, the parquetry blocks may be simply glued to the individual backing to form the boards. Each completed board is finished by running it through a suitable jointing and planing machine, by which it will be tongued and grooved and the parquetry surface simultaneously planed to the desired smoothness and polish.

The boards may be used in the construction of panels for walls and ceilings and for other analogous purposes as will be readily understood.

Having thus described the invention, I claim:—

1. The herein described method of mak-

ing parquetry boards comprising a base and a parquetry surface fixed thereto, which consists in combining a plurality of parquetry blocks, fastening base boards to the opposite faces thereof and severing the board at a point intermediate said blocks to provide duplicate units.

2. The herein-described method of making parquetry boards comprising a base and a parquetry surface fixed thereto, which consists in forming a multiple parquetry block, fastening base boards to the opposite faces thereof, dividing the block longitudinally into sections, fastening other boards to the exposed faces of said sections, and then dividing the block divisions of each section into individual sections, each forming a board embodying a base and a parquetry surface.
- 20 3. The herein-described method of making parquetry boards comprising a base and a parquetry surface fixed thereto, which consists in assembling and permanently uniting a plurality of parquetry block sections to 25 form a multiple block in which the block

sections alternately extend longitudinally at right angles to each other, fastening base boards to the opposite faces of the multiple block, and dividing the block longitudinally into separate boards each having a base and a parquetry surface.

4. The herein-described method of making parquetry boards comprising a base and a parquetry surface fixed thereto, which consists in assembling and permanently uniting 35 a plurality of parquetry block sections to form a multiple block in which the block sections are arranged in series alternately extending longitudinally and transversely of the multiple block, fastening base boards 40 to the opposite faces of the multiple block, and dividing the block longitudinally into separate boards each having a base and a parquetry surface.

In testimony whereof I affix my signature 45 in presence of two witnesses.

FRANCIS X. GANTER.
